COMMUNICATION SYSTEM

Harry J. Nichols, Point Pleasant, N. J.

Application August 27, 1941, Serial No. 408,505

12 Claims. (Cl. 178—69.5)

The present invention relates to synchronizing systems and more particularly to synchronizing systems holding the deviation from synchronism to the narrow limits required in facsimile or television operation and is an improvement on the system, as disclosed in applicant's United States Patent 2,111,153 granted March 15, 1938.

In devices of the prior art, as disclosed, for example, in said Patent 2,111,153, the degree of deviation from synchronism has been within the tolerances permitted in telegraphy. Such tolerances, however, have permitted a greater degree of deviation from synchronism than is permitted in facsimile or television operation. For example, in the system of said Patent 2,111,153, and in all such systems wherein a rotating contactor mechanism is employed for producing compensation controlling impulses, the degree of deviation from synchronism may be such as to distribute the received synchronizing impulse between two contact segments, whereby insufficient impulse power is distributed to the correction apparatus to permit of correction back to synchronism. Further, in such rotating contactor mechanisms, a marked deviation from synchronism is required before sufficient impulse force is delivered to the compensating apparatus, and further the amount of impulse force is proportional to the amount of deviation. In such devices, therefore, the correction force has proven insufficient until a deviation has occurred, which is greater than the amount of deviation permitted in facsimile or television operation.

One of the objects of the present invention, therefore, is to produce a system of synchronism that will obviate these undesirable characteristics existing in the prior art.

Another object is to provide a novel synchronizing system in which a single synchronizing impulse is employed to produce a pair of effects, and means controlled by each of said pair to produce different phase changing effects which completely counteract each other when unison is established.

A further object is to provide a novel system for synchronizing, in which the period of duration of the synchronizing pulse has little or no bearing upon the compensation effect produced, the mere existence of such a pulse, for any slight period, initiating a compensating effect, and means operable independently of the synchronizing pulse control the duration of such compensating effects.

Another object is to provide a novel synchronizing device in which switching means, con-

trolled by sharp cut off cam devices, are employed to precisely determine the initiation and period of duration of a compensating effect.

Still another object is to provide novel quick-
5 acting switching mechanism producing a sharp distinction between lag and lead of a controlled rotary device with respect to the time of reception of a synchronizing pulse.

Another object is to provide a novel synchronizing system in which the degree of compensation for deviation from synchronism is independent of the degree of such deviation.

A further object is to provide a novel differential gear mechanism for producing in a precise
15 manner a compensating effect independent of the degree of deviation from synchronism.

Still another object is to provide a synchronizing system comprising a first and a second
20 rotary device, means producing repeated pulses indicative of a chosen phase position of said first device, means producing substantial isochronism between said first and second rotary devices, means operable in response to said pulses for controlling said producing means, and means
25 including pulse multiplying means for producing a combined electrical and mechanical differential compensating effect to correct the deviation from synchronism of said second device with respect to said first device.

30 Other objects of the invention will be pointed out in the following description and claims and illustrated in the accompanying drawings, which disclose, by way of example, the principle of the invention and the best mode, which has been contemplated, of applying that principle.

35 In the drawings:

Fig. 1 is a purely schematic view illustrating the essential elements employed at both the sending and receiving station of one type of
40 facsimile system and illustrating, generally only, certain mechanism employed in transmitting a synchronizing pulse.

Fig. 2 is a side view, partly in section, illustrating in greater detail the phase correction
45 mechanism, as illustrated in Fig. 1.

Fig. 3 is a sectional view taken on line 3—3 of Fig. 2.

Fig. 4 is an end view illustrating the clutch mechanism of Fig. 2.

50 Fig. 5 is a fragmentary detailed view, illustrating the clutch disconnecting operation.

Fig. 6 is a plan view illustrating in more detail one of the elements of the cam contactor of Fig. 1.

55 Fig. 7 is a side view of the device of Fig. 6.

Figs. 8a, 8b and 8c are schematic views, illustrating different steps in the operation of the synchronizing control contacts, as controlled by the cam contactors of Fig. 1.

Figs. 9a to 9f, inclusive, are graphical illustrations of the sequence of operations involved in utilizing the synchronizing pulse at the receiver for production of synchronism.

Fig. 10 is a circuit diagram of one embodiment of the synchronizing system employed for control of the starting and phase control mechanism of the present invention.

Fig. 11 is a circuit diagram of another embodiment of synchronizing system employed.

Referring to the drawings and more particularly to Fig. 1, there is illustrated schematically therein the elements of one form of facsimile system to which the present invention may be applied and the elements employed in maintaining synchronism between a sending and a receiving station.

A drive motor M provided with a reduction gear box GB rotates at reduced speed a drive shaft 20a. Clutch mechanism CM controlled by a start magnet SM controls the rotation, by drive shaft 20a, of the phase correction mechanism PCM, described in detail later. A driven shaft 20b whose phase with respect to drive shaft 20a can be altered by operation of the phase correction mechanism, carries a drum D upon which is mounted the record or material to be scanned or the material upon which there is reproduced a facsimile of the record scanned.

Mounted on the drum D and extending axially thereof is a strip 21, which in the present instance is illustrated as a black strip, outside the field of graphic material carried by the drum.

Scanning mechanism is provided for scanning the record and for periodically producing and repeating a synchronizing pulse, which may comprise any well known scanning mechanism. An optical scanning mechanism is illustrated comprising a light source L, a focusing lens FL, a collector lens CL and a photocell PC. The optical mechanism can be translated axially with respect to the drum D, as indicated by the arrow. Upon rotation of drum D and axial translation of the optical mechanism, a light beam scans each elemental area of the record and also the black strip 21. The changes in light tonal values of the elemental areas scanned produce changes in light intensity, proportional to such changes, which changes in light intensity are transformed by the photocell into changes of an electrical quantity, in a manner well known. Such electrical changes are representative of the light tonal values of the elemental areas scanned and may be employed to modulate a carrier wave for transmission over a communication channel, represented generally as a line, in a well known manner. The amplifier modulator AM is employed to amplify the electrical changes and to modulate the carrier.

Upon each rotation of the drum D, the strip 21 is also scanned by the light beam to affect the photocell PC whereby electrical changes are produced which are transmitted over the line to constitute synchronizing signals. Since the strip 21 is scanned during the so-called "overlap" period, a time separation of the picture and synchronizing signals exists.

At the receiving station, the signals are demodulated and the synchronizing pulses are filtered from the picture signals, by any well known means, as for example by means such as dis-

closed in U. S. Patent No. 2,153,202. The picture signals may be employed to control mechanism well known for reproducing a facsimile of the record scanned, such reproducing apparatus not comprising any part of the present invention and therefore not being further described.

The synchronizing pulses, preferably of the form as illustrated in Fig. 9a, are employed in a novel manner to produce complete synchronism between a transmitting drum D, at one station, and a receiving drum at another station. Since the apparatus at each station may be similar, reference is made to Fig. 1 for the mechanism employed in producing synchronism.

15 The phase correction mechanism PCM, outlined in Fig. 1, is illustrated in greater detail in Figs. 2, 3, 4 and 5. Drive shaft 20a is driven by the motor M (Fig. 1), as described above, and carries a drive collar 22 (Fig. 2) connected to drive shaft 20a by a pin 23. The inner end perimeter of collar 22 is toothed to form a crown gear 22a which meshes, when the clutch is engaged, with the crown gear 24a (Fig. 4) of clutch sleeve 24 rotatably mounted on hub 25 of annular gear G1 mounted for rotation on shaft 20a. A double fingered annular spring member 24b (see also Fig. 4) is attached to sleeve 24 by notched openings (not shown) fitted to mating projections on sleeve 24. The fingers of spring member 24b extend in opposite directions and fit respectively between pairs of lugs 26, 26 provided on the outer face of gear G1 (Fig. 4). A stop pin 24c fastened to sleeve 24 engages with the slanting surface 27 of armature 28 (Fig. 5) upon rotation of clutch sleeve 24, when the armature is released by the start magnet SM upon deenergization of the same. As the sleeve 24 continues its rotation, pin 24c rides on the surface 27 of armature 28 (Fig. 5) until it is stopped by notch 28a, the transverse motion of pin 24c axially sliding sleeve 24 to the left (Fig. 2) to disengage the crown gear surfaces 24a and 22a to thereby disengage the clutch mechanism CM. Spring member 24b provides a spring bias urging the clutch to engaged position and serves to cushion the shock when the clutch is engaged. To engage the clutch, start magnet SM is energized, as described later, to attract its armature 28 whereby the pin 24c is released and spring member 24b urges the crown gear members 24a and 22a into engagement whereby shaft 20a drives the gear G1 through collar 22, sleeve 24 and spring member 24b engaging the lugs 26. Driven shaft 20b is aligned with the drive shaft 20a by a ball and socket connection 29. Mounted on shaft 20b by means of set screw 30 is an annular gear G2, similar in construction to gear G1. A third annular gear G3 is mounted for rotation on shafts 20a and 20b, intermediate gears G1 and G2 and is driven by the novel epicyclic mechanism now to be described.

65 Mounted on driven shaft 20b and intermediate gears G2 and G3 is an epicyclic disk ED2 provided with a notched periphery (see Fig. 3). 70 Mounted for rotation with and for rotation within the epicyclic disk ED2 is the twin pinion gear TP2, one of whose gears meshes with the annular gear G3 and the other with annular gear G2. A counterweight W2 is provided on disk ED2 to counterbalance the weight of pinion TP2. A similar epicyclic disk ED1 is mounted for rotation on drive shaft 20a and is provided with counterweight W1 and with the pair of twin pinion gears TP1 mounted for rotation 75 with and rotation within the epicyclic disk ED1

and engaging respectively with annular gears G1 and G3.

Mounted on base 31 is the retard magnet RM controlling a pivoted armature 32 provided with a toothed end 32a biased to open position by spring 33 and abutting a stop pin 34. In the normal or deenergized position, armature tooth 32a is free of the teeth of epicyclic disk ED2 (Fig. 2). Upon energization of magnet RM, as described presently, armature 32 is attracted, and tooth 32a engages a tooth of epicyclic disk ED2 to lock the disk against rotation. The advance magnet AM is similarly constructed and mounted to lock epicyclic disk ED1 upon energization of the magnet, as described presently. As shown in dotted outline, the bases 31 of magnets RM and AM are so mounted as to be bodily slidable, so that, if desired, in the normal or deenergized condition of the magnets, the epicyclic disks ED1 and ED2 are held by the respective teeth 32a. The preferred operation, however, is illustrated in solid lines (Fig. 2).

Upon energization of start magnet SM with consequent engagement of clutch mechanism CM; gears G1, G2 and G3 and epicyclic disks ED1 and ED2 and twin pinions TP1 and TP2 rotate as a unit whereby shaft 20b is driven by the drive shaft 20a, with no change in phase of 20b with respect to 20a. If the receiving mechanism is running slow with respect to the transmitting mechanism, the advance magnet AM is energized, as described later, its armature 32 is attracted and epicyclic disk ED1 is held against rotation. Gear G1 drives twin pinion TP1 which in turn differentially drives G3, ED2 and G2, as a unit, so that the phase of shaft 20b is advanced with respect to shaft 20a to thereby advance the phase of the receiver drum D (Fig. 1) without altering the speed of rotation of shaft 20a. If shaft 20b is rotating in advance of the transmitting drum, epicyclic disk ED2 will be held and gears G1, TP1 and G3 and disk ED1 will rotate, as a unit, to rotate twin pinion TP2 and differentially drive gear G2 to retard the phase of shaft 20b. When both the advance magnet and the retard magnet are energized, both disks ED1 and ED2 are held, and the shafts 20a and 20b are rotated, always in phase.

Referring to Figs. 1, 6, 7, 8a, 8b and 8c, the theory and construction of the synchronizing switch control means are illustrated therein. Each switch, such as the switch X1 (Fig. 10), comprises a pair of spring contactors, such as S1 and S2 (Fig. 8a) controlled by cams such as C1 and C2, respectively. As illustrated schematically in Figs. 8a, 8b and 8c, the spring contactors, such as S1 and S2, are held in open position for nearly one complete rotation of cams C1 and C2, mounted for rotation by shaft 20c (see also Fig. 1). As shaft 20c rotates, the cam C1 releases spring contactor S1 to engage spring contactor S2 (Fig. 8b), and switch X1 is thereby closed. As cams C1 and C2 continue to rotate, spring contactor S2 drops away from spring contactor S1 (Fig. 8c) and remains so disengaged until the positions of Fig. 8a are again assumed. Each of the cams C1 and C2, for example, is provided with a sharp drop off surface whereby the exact point of closure and opening of a switch such as X1, is sharply determined. As illustrated in Figs. 6 and 7, cam members C1 and C2 are mounted for rotation by shaft 20c. A follower 35, pivoted on shaft 36 rides on the evolute surface of cam C2, for example, (Fig. 7) its insulated end 35a engaging the spring contactor S2. Similarly, the

follower 35 of cam C1 rides on the surface of cam C1 and its insulated end 35a engages spring contactor S1 to maintain springs S1 and S2 in a separated condition. As follower 35 of cam C1 drops off the sharp edge of cam C1 (Fig. 8a), spring S1 engages spring S2 to close switch X1 (Fig. 8b). As cams C1 and C2 continue rotation, follower 35 of cam C2 drops off the sharp edge of cam C2, to disengage springs S1 and S2, as illustrated schematically in Fig. 8c. The drop off cam surface, provides a sharp line of demarcation between the open and closed positions of the respective switches X1, etc., whereby the deviation from synchronism is sharply ascertained and the kind of deviation is also ascertained, as described presently. As shown schematically in Fig. 1, cams C1 to C8, inclusive, control the spring contactors S1 to S8, inclusive, which in pairs, such as S1 and S2, comprise the switches X1, X2, X3 and X4, respectively, (Fig. 10).

Referring to Fig. 10, there is illustrated therein, in diagrammatic form, the circuit at a receiving station for utilizing the synchronizing pulses, according to one embodiment of the invention, to produce and maintain complete synchronism between the sending and the receiving drums D, by electrical control of the start magnet SM, advance magnet AM and retard magnet RM. The synchronizing signals and picture signals are received and demodulated and the synchronizing and picture signals are separated by the amplifier, demodulator, filter ADF. The picture signals are employed, in any desired and well known manner, to reproduce on receiving drum D, a copy or facsimile of the record at the sending station. The synchronizing pulses, of definite duration, and preferably square-topped, as illustrated in Fig. 9a, are applied to primary P of transformer T and appear in the secondary windings Sd1 and Sd2, as two discrete pulses of opposite polarity (see Fig. 9b) designed as e1 and e2, one marking the beginning of the synchronizing pulse and the other the termination thereof. It should be particularly noted that the synchronizing signals can be comparatively prolonged compared to picture signals, facilitating differentiation therebetween. It is further assumed that e1 can trip only, gas filled triode T1 and that e2 can trip only, gas filled triode T2. Gas filled triode T1 comprises a cathode, a grid Gr1 and an anode, the grid Gr1 being connected to the secondary Sd1 by the switch X1, comprising the spring contacts S1 and S2 (Fig. 8a). The plate of T1 is connected to one end of the coil of advance magnet AM, by switch X2, comprising spring contacts S3 and S4 (Fig. 9d), while the other side of the coil is connected to the coil of quick acting slow-release start magnet SM, the other end of whose coil is connected to the positive side of the battery B1 whose negative side is connected to the cathode of T1. A shunt circuit comprising resistor R5 and switch X5 is provided around start magnet SM, which shunt circuit is employed when the device is used as a transmitter.

The grid Gr1 is maintained at cut off by means of biasing battery B2 and grid resistor R1. The grid Gr2 of gas filled triode T2 is similarly connected to secondary Sd2 by switch X3 comprising spring contacts S5 and S6 (Fig. 9e) and the anode of T2 is connected by switch X4 comprising springs S7 and S8 (Fig. 9f) to one end of the coil of retard magnet RM whose other side

is connected to the coil of start magnet SM. Start magnet SM is therefore in the common return of the plate circuits of tubes T1 and T2.

In Fig. 11 there is illustrated a modification of the circuit of Fig. 10 which is more economical of construction than the circuit of Fig. 10 but produces generally the same result. Gas filled triodes T1 and T2, of Fig. 10, are replaced by vacuum tube triodes VT1 and VT2, respectively. The grid Gr1 of VT1 is connected to the secondary Sd1 through a neon lamp NL1 and switch X1 in series. One side of neon lamp NL1 is connected by resistor R3 and switch X2 to a positive source of potential. The plate of tube VT1 is connected directly to one side of the coil of advance magnet AM, and the start magnet SM is again in the common return for the plate circuits of two tubes, namely, VT1 and VT2. The grid Gr2 of vacuum tube VT2 is connected to secondary Sd2 by means of neon lamp NL2 and switch X3 in series, and positive potential is supplied to one side of neon lamp NL2 by way of resistor R4 and switch X4. The operation of the embodiment of Fig. 11 simulates the operation of the circuit of Fig. 10 but replaces the more expensive gas filled trigger tubes T1 and T2 of Fig. 10, by ordinary triodes VT1 and VT2 and the inexpensive neon lamps NL1 and NL2, while still obtaining the trigger action of the gas filled tubes of Fig. 10. Briefly, the operation of the circuit of Fig. 11 is as follows: Upon closure of switches X1 and X2, for example, a positive biasing potential is applied to neon lamp NL1. Vacuum tube VT1 is negatively biased, virtually to cut off, via battery B2. Upon reception of a synchronizing pulse in the primary P, the voltage e1 in secondary Sd1 raises the potential of neon lamp NL1 above the break down voltage, and lamp NL1 is ignited. Ignition of NL1 raises the potential of grid Gr1 of tube T1, in a positive direction, producing increased current flow in the anode circuit of tube VT1, as long as neon lamp NL1 is ignited. Switch X1 may be thereafter opened, without quenching the lamp NL1, and the flow in the plate circuit of tube VT1 continues until switch X2 is opened, removing the positive bias from lamp NL1 which is thereupon quenched, and the flow through the plate circuit of tube VT1 ceases. The action of tube VT2 is similar, except that NL2 is ignited solely by pulse e2 at the end of the synchronizing pulse. The operation of the tubes VT1, VT2 is therefore made to simulate the operation of the gas filled tubes T1 and T2, to control the operation of magnets AM, SM and RM, as will be described in detail presently.

Referring to Figs. 9a to 9f, inclusive, there is illustrated graphically, the timing of the operations of the several switches X1, X2, X3 and X4, with respect to the time of occurrence of the synchronizing pulse. The letter *i* represents the synchronizing pulse, e1 and e2, (as stated above) the discrete pulses appearing in secondaries Sd1 and Sd2, respectively; t1 to t8, inclusive, timing points at which the switches open or close; and S1 to S8, inclusive, in pairs, such as S1 and S2, for example, comprising the respective switches X1, etc.; illustrate the action of the individual spring contacts controlled by cams C1 to C8, inclusive (Fig. 1). The timing charts of Figs. 9a to 9f, inclusive, represent either the "start" or "unison" condition.

The sequence of events, at "start" is as follows: It is assumed that switches X1 and X2 (Fig. 10) are closed, so that Gr1 is connected to the

secondary Sd1 and the anode circuit of T1 is closed through the coils of advance magnet AM and start magnet SM. Gas filled tube T1 is biased below the "trip" voltage. At point t1 (Figs. 9a and 9b) pulse e1 is applied to grid Gr1, to trip T1, producing a flow of current in the plate circuit of T1 to thereby energize the advance magnet AM and the start magnet SM. Upon energization of start magnet SM, its armature 10 (Fig. 2) is attracted, to release clutch sleeve 24 and permit engagement of the clutch mechanism CM, whereby the drum D at the receiving station is started into rotation approximately in step with the drum at the sending station. Upon 15 energization of advance magnet AM, its armature 32 is attracted and tooth 32a engages and holds epicyclic disk ED1 whereupon the differential action of the phase corrector mechanism PCM advances the phase of shaft 20b with respect to shaft 20a. Immediately after drum D at the receiver starts to rotate, cam C2, controlling spring contactor S2 (Fig. 8c), permits spring S2 to drop, thereby opening switch X1 and disconnecting grid Gr1 from secondary Sd1 (see also 20 Fig. 9c). Even though switch X1 is opened, current flow through the plate circuit of gas filled tube T1 continues until cam C4 allows the spring contact S4 to drop (Fig. 9d) thereby opening switch X2 in the plate circuit of T1, to quench 25 T1. It is seen, therefore, that the time of triggering on of tube T1 is sharply defined with respect to the pulse *i*, but that once tube T1 is triggered, the correcting effect is maintained for a predetermined period, regardless of the amount 30 of deviation from synchronization, so that full corrective effect is applied upon the slightest deviation from synchronization.

Under normal operating conditions, shortly before the synchronizing pulse *i*, is terminated, at 40 t2 (Fig. 9a), cams C5 and C1 permit spring contacts S5 (Fig. 9e) and S1 (Fig. 9f), respectively, to drop, thereby closing switches X3 and X4 (Fig. 10) to render tube T2 operative, so that pulse e2 triggers tube T2. When T2 is thus triggered, its plate current flow continues for a predetermined period (Fig. 9f) whose period is completely independent of the amount of deviation from synchronization, so that full corrections are 45 applied, upon the slightest deviation from synchronization. As is seen in Figs. 9a to 9f, inclusive, both an advancing and a retarding effect are produced, which are equal and opposite, when the device is at unison. There is, therefore, continuously maintained, a dynamic effect maintaining synchronization, instead of the usual static effect, which usual static effect requires a considerable change of condition before any correction effects are applied.

On the very first revolution, after clutch mechanism CM is engaged; due to the slight delay caused by clutch action, inertia, etc., switches X3 and X4 are not closed until after the occurrence of pulse e2, so that only an advancing phase effect is produced, which gives the mechanism a boost towards unison, to overcome the initial lag.

As is seen from Fig. 9e, at point t3, cam C6 permits spring contact S6 to drop thereby opening switch X3, and at point t4, cam C4 permits switch contact S4 (Fig. 9d) to drop, to open switch X2, as described above. At point t5, cam C8 permits switch contact S8 (Fig. 9f) to drop to open switch X4, and at point t6, cams C1 and C3 70 permit spring contacts S1 and S3 to drop there-

by closing switches X_1 and X_2 (Fig. 10) and preparing tube T_1 for operation by the next synchronizing pulse i . Due to the slight delay in starting, as described above, it may be assumed that switches X_1 and X_2 are in such closed position, during this second synchronizing pulse, so that advance magnet AM is again energized and magnet SM is sustained. The phase of the receiving drum is therefore advanced until the condition of unison, as illustrated in Figs. 9a to 9f, inclusive, is achieved. At unison, as stated above, switches X_3 and X_4 close before the end of the synchronizing pulse i , discrete pulse e_2 , trips on T_2 , and the retard magnet RM is energized, whereby a phase retarding effect is produced, equal to the phase advancing effect, and the receiving drum is no longer advanced in phase but is held at unison with the sending drum. Should drum D at the receiver tend to lag, advance magnet AM only, is energized, and the phase is advanced; should drum D at the receiver tend to lead, retard magnet RM only, is energized and the phase is retarded. Synchronism is therefore continuously maintained by changing the phase of the receiving drum D , when necessary, without altering the speed of rotation of the driving motor M at the receiver.

By inspection of Figs. 9a to 9f, inclusive, it is seen that due to the sharp control of switches X_1 and X_3 , the correcting mechanism at the receiver distinguishes sharply between a lag in phase on one hand and a lead in phase on the other hand, so that not only is the corrective force quickly applied, but the proper kind of corrective force is quickly ascertained and applied. It is readily apparent, therefore, that the sharp drop off cams, controlling the control switches, produce a sharp discrimination between the kind of corrections needed, and that the combined mechanical and electrical differential action produces prompt phase correction, dynamically, and in the proper direction.

Novel means are therefore provided which sharply distinguish, within a narrow zone, between two kinds of corrections required upon deviation from synchronism, a dynamic corrective condition is continuously maintained, and combined mechanical and electrical differential correction is produced to obtain accurate control of synchronism to a degree of precision required by facsimile, and such correction is continuously, quickly and efficiently produced and the correction applied is completely independent of the amount of deviation from synchronism, so that a full corrective effect is applied upon the slightest deviation from synchronism.

While there has been shown and described and pointed out the fundamental novel features of the invention as applied to a plurality of embodiments, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a system for control of one rotary device by another, in combination, drive means for rotating said one rotary device substantially isochronously with said other device, means for advancing the phase of said one device with respect to said other device while maintaining the speed of said drive means constant, means for retarding

- the phase of said one device with respect to the other while maintaining the speed of said drive means constant, means producing repeated electrical synchronizing impulses representative of a predetermined phase position of said other device, means for transmitting said impulses, means for receiving said impulses and producing a pair of effects in response to reception of each of said impulses, a pair of gas filled triodes, means selectively applying one of said effects to the grid of one of said gas filled triodes and the other effect to the grid of the other of said triodes, means controlled by either of said triodes for rendering said drive means effective to produce approximate synchronization between said devices, means controlled by one of said triodes for rendering said phase advancing means effective and means controlled by the other of said triodes for rendering said phase retarding means effective.
2. In a synchronizing system for control of one rotary device by another, in combination, means producing repeated electrical synchronizing impulses representative of a predetermined phase position of said other device, means for transmitting said impulses, means for receiving said impulses and producing a pair of effects in response to reception of each of said impulses, drive means for rotating said rotary device substantially isochronously with said other device, means for rendering said drive means effective to produce approximate synchronization between said devices, means for advancing the phase of said one device with respect to said other device while maintaining the speed of said drive means constant, and means for retarding the phase of said one device with respect to said other device while maintaining the speed of said drive means constant, one of said pair of effects controlling said rendering means and one of said phase changers, and the other of said pair controlling said rendering means and the other of said phase changers.
3. In a system for control of one rotary device by another, in combination, means producing repeated electrical synchronizing impulses representative of a predetermined phase position of said other device, means for transmitting said impulses, means for receiving said impulses and producing a pair of effects in response to reception of each of said impulses, drive means for rotating said one rotary device substantially isochronously with said other device, means for rendering said drive means effective to produce approximate synchronization between said devices, means for altering the phase of said one device with respect to said other device while maintaining the speed of said drive means constant, means controlled by said impulses for initiating operation of said drive means and of said altering means, means for determining the period of effectiveness of said drive means, and means comprising a sharp drop off cam for controlling said determining means and the application of said impulses to said controlled means.
4. In a system for control of one rotary device by another, in combination, drive means for rotating said one rotary device substantially isochronously with said other device, means for advancing the phase of said one device with respect to the other while maintaining the speed of said driving means constant, means for retarding the phase of said one device with respect to the other while maintaining the speed of said drive means constant, means producing repeated electrical synchronizing impulses representa-

tive of a predetermined phase position of said other device, means for transmitting said impulses, means for receiving said impulses and producing a pair of effects in response to reception of each of said impulses, a pair of triodes, a pair of gas filled tubes respectively connected to the grids of said triodes, means selectively applying one of said effects to one of said gas filled tubes and the other effect to the other tube of said pair, means controlled by either of said triodes for rendering said drive means effective to produce approximate synchronization between said devices, means controlled by one of said triodes for rendering said phase advancing means effective, and means controlled by the other triode for rendering said phase retarding means effective.

5. In a synchronizing system for control of one rotary device by another, in combination, drive means for rotating said rotary device substantially isochronously with said other device, means for advancing the phase of said one device with respect to the other while maintaining the speed of said drive means constant, means for rendering the phase of said one device with respect to the other while maintaining the speed of said drive means constant, means producing repeated electrical synchronizing impulses representative of a predetermined phase position of said other device, means for transmitting said impulses, means for receiving said impulses comprising a primary of a transformer, a secondary for said transformer, a pair of gas filled triodes, means including switching means for connecting one end of said secondary to the grid of one of said triodes, means including switching means for connecting the other end of said secondary to the grid of said other triode, means for rendering said drive means effective, means for rendering said phase advancing means effective and means including switching means connecting said first and second rendering means in the plate circuit of one triode, means for rendering said phase retarding means effective and means including switching means for connecting said first rendering means and said last rendering means in the plate circuit of said other triode, and adjustable cam means having a sharp drop off controlling said switching means, respectively, to initiate operation of said triodes under control of said impulses and to control the duration of operation of said advancing and retarding means independently of said impulses.

6. In a synchronizing system for control of one rotary device by another, in combination, means producing repeated electrical synchronizing signals representative of a predetermined phase position of said other device, means for transmitting said signals, means for receiving said signals, means controlled by each received signal for producing two discrete impulses of opposite polarity, and means controlled by the said discrete impulses for altering the phase of said one device, said phase altering means including differentially operable means which are responsive to, and selectively rendered effective by, the said discrete impulses of opposite polarity.

7. In a synchronizing system for control of one rotary device by another, in combination, means producing repeated electrical synchronizing impulses representative of a predetermined phase position of said other device, means for transmitting said impulses, means for receiving said impulses, drive means for rotating said rotary device substantially isochronously with said

other device to maintain approximate synchronization between said devices, and means for altering the phase of said one device with respect to said other device while maintaining the speed of said drive means constant, said means comprising means controlled by said received impulses for producing a combined mechanical differential and electrical differential compensating effect.

10. 8. In a synchronizing system for control of one rotary device by another, in combination, means producing repeated electrical synchronizing impulses representative of a predetermined phase position of said other device, means for transmitting said impulses, means for receiving said impulses, drive means for rotating said one rotary device substantially isochronously with said other device to maintain approximate synchronization between said devices, means controlled by said impulses for advancing the phase of said one device with respect to said other device while maintaining the speed of said drive means constant, means controlled by said impulses for retarding the phase of said one device with respect to said other device while maintaining the speed of said device constant, and means including switching means controlled by sharp drop off cam means sharply differentiating between a lag and a lead in said one device with respect to said other device for applying said pulses selectively to said advancing or to said retarding means.

9. Phase correcting mechanism comprising a drive shaft, a driven shaft, means for coupling said drive shaft to said driven shaft, means controlled by a synchronizing pulse for rendering said coupling means effective, a double fingered annular spring member attached to said coupling means, an annular gear, means interconnecting said gear and said spring member whereby said gear is rotated by said drive shaft when said pulse controls said rendering means, an epicyclic member mounted for rotation, a pair of gears mounted for rotation with and rotation within said member, a second annular gear, said pair of gears respectively engaging with said first and said second annular gears, a second epicyclic member, a pair of gears mounted for rotation with and rotation within said member, a third annular gear connected to said driven shaft, said second pair of gears engaging, respectively, with said second and third annular gears, means alternately locking and freeing said epicyclic means for rotation selectively, one of said epicyclic means producing advance of phase of said driven shaft and the other producing a retardation of the phase thereof with respect to said drive shaft.

10. Phase shifting mechanism comprising a drive shaft, a driven shaft, an annular gear driven by said drive shaft, an annular gear connected to said driven shaft for driving the same, a third annular gear intermediate said first two gears, a pair of epicyclic members, each mounted for rotation, a pair of gears mounted on each of said members for rotation therewith and rotation therein, the gears of one pair meshing, respectively, with said first and said third annular gear and the gears of said other pair meshing, respectively, with said second and said third annular gears, and means for alternately locking and releasing each of said epicyclic members for rotation to produce a change in phase of said driven shaft with respect to said drive shaft.

75. 11. Phase shifting mechanism comprising a

drive shaft, a driven shaft, a gear driven by said drive shaft, a gear on said driven shaft for rotation thereof, a third gear intermediate said first two gears, a pair of epicyclic members, each mounted for rotation, gears carried by said members respectively and meshing with said first and second and with said second and third gears, respectively, individual means including a solenoid for locking and releasing said epicyclic members respectively upon energization and de-energization, respectively, of said solenoids and means for shifting said individual means with respect to said epicyclic members whereby said epicyclic members respectively are locked and released upon deenergization and energization, respectively, of said solenoids.

12. In a synchronizing system for control of one rotary device by another, in combination, means producing repeated electrical synchronizing impulses of sustained period representative of a predetermined phase position of said other device, means for transmitting said impulses,

means for receiving said impulses, drive means for rotating said one rotary device substantially isochronously with said other device to produce approximate synchronization between said devices, means for advancing the phase of said one device with respect to said other device while maintaining the speed of said driving means constant, means for retarding the phase of said one device with respect to said other device while 10 maintaining the speed of said driving means constant, means producing from each of said sustained impulses a pair of practically instantaneous pulses selectively effective to control said advancing and retarding means, and means 15 sharply contrasting the period of said sustained impulses with the timed rotation of said one device to distinguish between advance or retardation of said one device with respect to said other device and selectively rendering one only of said 20 instantaneous pulses effective.

HARRY J. NICHOLS.
